WORK INDEXING MECHANISM

Edgar J. Gardner, Santa Susana, Calif., assignor of small percentages to various assignees

Filed Dec. 9, 1957, Ser. No. 701,630

17 Claims. (Cl. 112—65)

This invention relates to sewing machines, more particularly of the automatic type used for making buttonholes, and the present invention has particular reference to an automatic work retaining and feeding attachment for such machines.

One of the principal objects of the present invention is to provide a mechanism for attachment to sewing machines of the automatic buttonhole-making type, which attachment retains the work in position on the machine and automatically presents to the sewing machine needle and its appurtenances successive, spaced portions of the work for step-by-step making of individual buttonholes.

A further object of the present invention is to provide automatic work retaining and feeding attachments for buttonhole machines, which attachments make it possible for a single operator to simultaneously operate two or more buttonhole machines.

Still another object of the present invention is to provide a fully automatic and wholly fool-proof mechanism for retaining and feeding the work through a buttonhole machine in synchronization with the operation thereof for proper and predetermined spacing of buttonholes on said work, and which mechanism is relatively inexpensive and easily attached to existing buttonhole machines without substantial modification thereof.

Other objects and advantages of the present invention will be readily apparent from the following detailed description of a preferred embodiment thereof when read in connection with the accompanying drawings.

In the drawings:

Figure 1 is a top plan view of a conventional buttonhole machine having attached thereto the mechanism of the present invention, with a portion of the buttonhole machine broken away.

Figure 2 is a fragmentary view similar to Figure 1 and illustrating the work in place on the mechanism.

Figure 3 is a sectional elevation taken substantially on the line 3—3 of Figure 1.

Figure 4 is a sectional elevation taken substantially on the line 4—4 of Figure 1.

Figure 5 is a sectional elevation taken substantially on the line 5—5 of Figure 1.

Figure 6 is a sectional elevation taken substantially on the line 6—6 of Figure 1.

Figure 7 is a fragmentary sectional elevation similar to Figure 3, but illustrating the position of the parts when the driving shoe is in the disengaged position.

Figure 8 is a sectional elevation taken substantially on the line 8—8 of Figure 1.

Figure 9 is a sectional elevation taken substantially on the line 9—9 of Figure 3.

Figure 10 is a sectional elevation taken substantially on the line 10—10 of Figure 3.

Figure 11 is a diagrammatic top plan view of the clutch actuating mechanism.

Figure 12 is a diagrammatic top plan view of the presser foot operating mechanism.

2

Figure 13 is a fragmentary top plan view similar to Figure 1, but on an enlarged scale and illustrating a portion of the clutch actuating mechanism.

Figure 14 is a sectional elevation taken substantially on the line 14—14 of Figure 1.

Figure 15 is a fragmentary side elevation, illustrating the work hold-down roller.

Referring now to the drawings, the attachment of the present invention is designed to be utilized in conjunction with conventional sewing machines designed to make buttonholes. Before describing in detail the attachment of this invention, the salient features of the conventional sewing machine itself will be discussed briefly, and particularly those sewing machine parts and mechanisms operated by the present attachment.

The specific sewing machine so illustrated is constructed substantially in accordance with the disclosure of U.S. Patent Nos. 1,839,823 and 2,338,611 to Wood, to which reference may be had for a more complete disclosure of the sewing machine construction. The sewing machine is especially adapted to form stitches about the edges of a buttonhole and to that end it is provided with a laterally jogging and endwise reciprocating needle 22 which cooperates with a conventional shuttle 23 to form zigzag stitches. By means of a shiftable work clamp or presser foot 24, the work is moved with respect to the needle so that the stitches are arranged in two spaced rows, one row along each side of the space which is severed to provide the buttonhole aperture.

The sewing machine is mounted on a suitable table 25 to which is also secured a motor (not shown) connected by a belt transmission to drive the main shaft 26. The needle is operated through a clutch and stop motion assembly (not shown) operably connected to the drive shaft 26 within the housing 30. Operation of the clutch and stop motion mechanism is accomplished by means of a vertically reciprocable, spring-loaded pull rod 31 which carries a belt-shifting arm (not shown) and a spring loaded stop-plunger (not shown). Depression of the pull rod moves the stop plunger out of engagement with a stop-cam (not shown) carried on the drive shaft and also engages the clutch mechanism thus causing the drive shaft to be driven by the motor and actuating the needle mechanism to begin the stitching operation. A latch lever (not shown) is provided to engage the pull rod 31 and maintain the clutch and stop-motion mechanism in running position. The number of stitches which the machine will make each time the clutch and stop-motion mechanism is shifted into running position depends upon the speed ratio at which a pattern cam (not shown) is actuated. This cam serves to trip the latch lever and release the pull-out rod, thus automatically disengaging the clutch and stopping the sewing machine.

The pull rod 31 is conventionally depressed for operation of the machine by means of a foot treadle or knee shift. The present invention includes power means for automatically depressing this pull rod as will be fully explained hereinafter and accordingly the foot treadle and/or knee shift are dispensed with in use of the attachment of this invention.

The sewing machine is also provided with a buttonhole cutting mechanism which, for clarity of illustration, is not shown in the drawings.

The work clamp 24 includes an upper clamp jaw 40 which is carried by a lever 41 pivoted at 42 to the base 44 of the clamp. The clamp jaw 40 is normally biased into cloth gripping position by a spring 43 which engages the jaw 40. The lever 41 is engaged by a roller 45 carried by a link 46 pivoted to a crank arm 47 fixed to a rotatably mounted shaft 48. The crank arm is provided

with an extension 49 which is conventionally operably connected to a foot treadle or knee shift, but here again, these manually operated devices are dispensed with, the attachment hereinafter described including power means for controlling the operation of the work clamp.

The attachment of the present invention includes a framework generally indicated 50 and comprising, in effect, a pair of connected tables 51 and 52, one on either side of the sewing machine proper.

The attachment includes power means for controlling the operation of the work clamp, and as shown in the drawings, these means may include a solenoid 60 on the table 52 which actuates a rod 61 mounted for longitudinal reciprocation in suitable bearing blocks 62. The end of the rod remote from the solenoid carries a yoke 63 on which is journaled a roller 64 contacting the lower portion of a crank arm 65. The arm 65 is secured to a shaft 66 mounted for rotation in suitable bearing blocks 67. Also carried on the shaft 66 is a substantially horizontal crank arm 68 which is secured to the extension 47 by means of a spring 69. A pair of micro switches 70 and 71 are pivotally mounted on the table 52 in positions to contact switch actuating stop elements 73 and 74 respectively. A pair of adjustably mounted collars 75 and 76 are provided on the rod 61 in positions to contact the respective switches 70 and 71.

Mounted on the table 52 on the other side of the rod 61 is a solenoid 78 operably connected to a spring-loaded bell crank 79, the crank being provided with a bulged end portion adapted to move into the space between the collar 76 and a third collar 76a as shown in Figure 1, the end of the crank being in contact with the collar 76a and functioning as a latch to prevent movement of the rod 61 to the left as seen in Figure 1.

Means are provided for power control of the pull rod 31 and hence also of the clutch and stop motion assembly. As shown in the drawings, these means may include a solenoid 80 on the table 51 which actuates a rod 81 mounted for longitudinal reciprocation in suitable bearing blocks 82. The end of the rod remote from the solenoid carries a yoke 83 on which is journaled a roller 84 contacting the lower portion of a crank arm 85. The arm 85 is secured to a shaft 86 mounted for rotation in suitable bearing blocks 87. Also carried on the shaft 86 is a substantially horizontal crank arm 88 which is pivotally connected to the pull rod 31 as shown in Figure 1.

The rod 81 carries a pair of adjustable, spaced collars 89 and 90 which are adapted to actuate a toggle switch 91 mounted on a plate 92 on the table 51 on one side of the rod. Mounted on the underside of the plate 92 is a solenoid 93 operably connected to one arm of a spring-loaded bell crank 94 which is pivoted to the underside plate 92. The other arm of the bell crank is pivotally connected to a plate 95 slidably mounted on the plate 92, the connecting pivot pin 96 extending through a slot 97a in the plate 92. Pivotally connected to the plate 95 is a micro switch 97 which carries an actuator finger 98. A spring 99 connected at one end to the plate 92 and at the other end to the switch normally biases the switch out of contact with a switch actuating stop 100 provided on the plate 95. The switch finger 98 is adapted to be contacted by an adjustable collar 101 mounted on the rod 81. A spring 102 extending between the collar 101 and the bearing block 82 serves to take any play out of the rod 81.

Means are provided for retaining or supporting the work in position on the sewing machine and as shown in the drawings these means may include a work-supporting table 110. The table, preferably of sheet metal, is generally horizontal and roughly U-shaped in plan, being provided with upstanding work-alignment portions 111 at the ends of each leg of the U and having an arcuate, downwardly-turned front edge 112. A pair of conven-

tional, quick-acting, lever-type clamps 113 provided with elongated foot members 114 is secured adjacent each end of the table for retention of the work thereon.

Means are provided for mounting the table for longitudinal and transverse sliding movement. As shown in the drawings, the table is adjustably secured at either end, by means of the key slots 115 and the screws 116, to one of a pair of transversely slidable support members 116a and 117. As seen in Figure 1, these support members are generally U-shaped in plan and are otherwise substantially identical.

The support member 117 is mounted for slidable movement with respect to a block member 120, the block member being provided with a pair of rod supports 121 extending forwardly from the front side thereof, each extending through one of a pair of slideway bores 122 in the support member 117. Similarly, the support member 116a is mounted on the block member 124 which is provided with rods 125 extending through corresponding bores in the member 116a.

Means are provided for reciprocating the support members 116a and 117, and hence also the table 110 and the work, simultaneously with and to the same extent as the conventional transverse reciprocatory movement of the work clamp 24, i.e., movement in the directions of the arrows of Figure 5. As shown in the drawings, these means may include a pin 130 carried on a vertical plate 131 secured to a horizontal plate 131a which in turn is secured to the reciprocating clamp base 44. Pivoted at one end to the pin 130 is a lever 132, the other end of which is pivotally connected to the upper end of a crank arm 133 (see especially Figures 5, 8 and 9). The lower end of the arm is carried on a rotatable shaft 135 which extends completely across the entire framework 50, being journaled in the end plates 136 and 137 and in the intermediate support plates 138 and 139. Turning of the shaft in response to movement of the lever is transmitted into identical movement of the support member 117 by means of a pair of crank arms 140 carried on the shaft, one adjacent the intermediate support plate 139 and the other adjacent the end plate 137. Each of the arms 140 is pivoted at its upper end to a rod 145 which terminates short of the plates 137 and 139 and which extends through a longitudinal slot 146 in the upper portion of the support member 117 (see Figures 3, 4 and 7), the slot being provided with a pair of guide rods 148 to transmit the arcuate movement of the rod 145 into horizontal planar movement of the support member. Similarly, the shaft 135 carries a pair of crank arms 150 which are pivoted to a rod 151 which engages in an identical slot in the support member 116a.

Means are provided for intermittently moving the table longitudinally in synchronization with the operation of the needle and work clamp mechanisms for step-by-step feeding of the work and the automatic production of any desired number and spacing of buttonholes on the work. As shown in the drawings, these means may include a motor 160 provided with a belt transmission 161 for continuously driving a lead screw 162. The screw extends completely across the right-hand side of the framework and is journaled in suitable bearings in the end and support plates 137 and 139. As shown best in Figure 10, the screw extends through an oversize aperture 163 in the block member 120.

As seen best in Figures 9 and 10, the block member 120 is formed of two identical parts joined in spaced relation by means of a bushing 165 and a spacer 166. The member 120 is supported for longitudinal sliding movement on the framework by means of a pair of rods 170 and 171, the rod 170 extending through the bushing 165 and the rod 171 extending through a slot 173 extending upwardly in the block member. The block members 120 and 124 are rigidly tied together by means of a rod 175 connected to the lower portions of each of the

block members, the block member 124 being carried on rods 170a and 171a.

Carried on the block member 120 for operable movement with respect to the lead screw 162 is a shoe member 180 provided with half threads engageable with the threads of the lead screw. The shoe member is secured to a yoke member 181 (see Figures 3 and 7) provided with a bushing 182 and pivoted thereby to the rod 171 intermediate the spaced portions of the block member 120.

Power means are provided for engagement and disengagement of the shoe member with the lead screw and as shown in the drawings, particularly Figure 3, these means may include a pair of mutually opposed solenoids 184 and 185, each connected by means of a pivot pin 186 to a lever 187 pivoted at the lower end thereof to the plate 139 and pivoted at the upper end thereof to one end of a generally horizontal arm 190. The arm 190 is pivotally connected at the other end to the upper end of a crank arm 191 which is carried on a shaft 192 extending between and journaled in the end plates 137 and 139. Carried on the shaft 192 is a pair of crank arms 193 and 194 which support a rod 195 extending longitudinally of the framework just short of the plates 137 and 139. The shaft 192 operates between a pair of spaced pins 196 and 197 carried on the rear wall of the yoke member 181 (compare Figures 3 and 7).

The shoe 180 is resiliently latched in the engaged and disengaged positions by means of a spring-loaded latch rod 198, the lower end of which is adapted to seat in a slot 199 in the upper end of the lever 187. The upper end of the rod extends through a tapered opening 198a in an L-shaped bracket 198b.

Hold-down means are provided for maintaining the proper position of the work as it passes under the work clamp 14. These means may include a canted roller 200 which, because of the angle of inclination of its axis of rotation as seen in Figures 2 and 15, tends to pull the work toward the sewing machine, i.e., to the left as seen in Figure 15. As shown, the roller 200 is mounted for free rotation of an L-shaped bracket 201 which is pivotally connected to a block 202 secured to the stationary sewing machine base 203. A spring 204 biases the roller into contact with the work.

The means for initiating control of the intermittent longitudinal motion of the table 110 includes a plurality of micro switches 210 adjustably spaced on the framework a distance apart exactly equal to the desired spacing of the buttonholes to be made in the work. Each of the switches is mounted on a track formed by a pair of spaced bars 212 extending between the plates 137 and 139, each switch being releasably secured thereto by means of a bolt 214. A ruler 215 or other appropriate indexing device is mounted on one of the bars 212 for assisting the selective positioning of the switches. Each switch is provided with a spring actuator 220 and an L-shaped limit bracket 221.

The switches are actuated by a generally L-shaped arm 230 pivotally connected to the yoke member 181 as best seen in Figures 7, 9 and 14. A spring 231 normally holds the arm 230 in the position shown, against a stop 232, but permits deflection of the arm after initial contact with the switch actuator 220.

A stepped switch actuator 240 (Figure 9) is adjustably secured to the block 120 in position to actuate the roller switch arms 241, 242 and 243 of the switches 244, 245 and 246 upon completion of travel of the table 110. The functions of these switches will be described below.

In operation of the attachment of this invention, the operator first clamps the work, such as the shirt 250, on the table 110. It will be understood that for maximum efficiency the operator will be tending at least two such sewing machine and attachment assemblies so that the other machine or machines will be in buttonhole-making operation during this clamping step. Following the clamping, the operator presses the start button (not shown), thus

energizing the solenoid 78 and pivoting the bell crank 79 out of contact with the collar 76. This permits the work clamp 24 to come down and engage the work under the influence of the spring, which in turn moves the rod 61 to the left as shown in Figure 12. During this operation, the collar 75 trips the switch 70 which is connected to the solenoid 80, thus energizing the solenoid and moving the rod 81 to the right. This causes the pull rod 31 to be depressed, by means of the rod's actuation of the crank arm 85 and in turn the arm 88, thus engaging the clutch, disengaging the stop motion mechanism and causing the sewing to begin.

As the rod 81 moves to the left the collar 90 moves the toggle of the switch 91 from the "off" to the "on" position. This switch is connected to the solenoid 80 and by the time the rod 81 has moved from the extended position of Figure 13 to the retracted position of Figure 11 the toggle switch is "on" and de-energizes the solenoid. This has no effect upon the position of the rod 81, however, since sewing is still going on, the pull rod 31 being locked in the depressed position. This in effect locks the rod 81 against movement from the position of Figure 11. It will also be seen from a comparison of Figures 11 and 13 that the collar 101 has moved to the left with the rod 81, thus permitting the switch 97 and its plate 95 to move toward the rod 81 until the finger 98 assumes the position of Figure 11 wherein it is in contact with the lateral side of the collar 101.

Upon completion of the sewing cycle for the first buttonhole, the pattern cam mechanism automatically re-

leases the pull rod 31 to the original extended position. This, through the crank arm assembly described above, moves the rod 81 back to the right to the position of Figures 1 and 13. In so doing the collar 101 moves the finger 98 and the switch 97 pivots into contact with the stop 100, thus tripping the switch. This switch is connected to the solenoids 60 and 184 and hence energizes these solenoids. The solenoid 60 then pulls the rod 61 and its appurtenances to the right from the extended position of Figure 12 to the original position of Figure 1. This pulls the work clamp 24 up out of contact with the work and the latch crank 79 re-engages the collar 76a to hold the work clamp in this position. The energization of the solenoid 184 causes the lever 190 and crank 191 to move to the left from the position of Figure 7 to the position of Figure 3. At the same time the free end of the crank arm 193 is moved downwardly, pivoting the yoke 181 to bring the shoe 180 into engagement with the continuously turning lead screw 162 and thus causing the table 110 and the work to be fed to the right as seen in Figures 1 and 2.

As the rod 61 completes the movement to the right described in the above paragraph, the collar 76 trips the switch 71. This switch is connected to the solenoid 93 and thus energizes it to cause it to move the bell crank 94 which in turn pulls the switch 97 back to the open position of Figure 13, thus de-energizing the solenoids 60 and 184.

The table 110 and the work continue to move to the right until the arm 230 trips the left-most (as seen in Figure 1) switch 210. This switch, being connected to the solenoids 78 and 185 energizes both solenoids so that simultaneously the latch 79 is released to start the entire cycle described above, and the shoe 180 is disengaged to stop the table 110, positioning the work for the sewing of the next buttonhole. The disengagement of the shoe 180 is accomplished by the solenoid 185 through the same mechanical linkage and crank system as described in connection with the operation of the solenoid 184 except that the motions are exactly the reverse.

It will be understood that the above cycle is repeated a number of times equal to the remaining number of switches 210. After the last switch 210 has been tripped and the cycle repeated for the last time to make the lowermost buttonhole on the shirt, the stepped switch actuator trips, in sequence, switches 244, 245 and 246. Normally closed switch 244 cuts off the power supply to the

solenoid 78, normally open switch 245 de-energizes the solenoid 185 to disengage the shoe 180, and normally closed switch 246 cuts off all power supply to the attachment.

The completed work is then removed from the table 110, the table is moved by hand back to the starting position, and the entire operation is repeated.

It is to be understood that the conventional work clamp 24 shown and described herein reciprocates, when in the depressed position, in a path defined herein as "transverse," to move the portion of the work which is under the needle in the desired manner to produce the buttonhole stitching. Those skilled in the art will understand that this is not wholly linear motion, and that at the ends of the buttonholes, the clamp moves a slight amount in a direction substantially normal to the buttonhole so as to permit stitching of two rows of stitches. This slight "normal" motion is not transmitted to the table 110, being taken up in the resiliency of the work itself.

Although not shown in the drawings, it is to be understood that automatic clamping means may be substituted for the manual means shown, or the clamps shown may be modified to render them automatic or semi-automatic in operation. For example, a cam or cams may be mounted on the framework and operably connected to the clamps 113 to cause their automatic opening at the end of the operation and automatic closing at the start thereof.

It is to be further understood that the attachment of the present invention is readily adapted to be attached to any standard type of sewing machine adapted to the making of buttonholes. A slight modification of the attachment shown and described above would be required for use of the attachment with the "Reese" type of machine such as is described in U.S. Patents Nos. 488,028, 494,280, and 713,764. Inasmuch as this type of machine does not utilize the pull rod 31, the control means for the rod 31 shown and described herein would not be required.

Having fully described my invention, it is to be understood that I do not wish to be limited to the details set forth, but my invention is of the full scope of the appended claims.

I claim:

1. In a buttonhole making machine of the type having a needle and a co-operating work clamp reciprocable in a transverse direction, an attachment, in combination with said needle and work clamp, including means for supporting the work in operative position with a portion thereof under said work clamp, means for moving said work supporting means simultaneously with and in a path duplicating the transverse movement of said work clamp, and means operable in timed relation with said needle and said work clamp for intermittently feeding said work supporting means longitudinally past said work clamp for the automatic production of a plurality of button holes in said work.

2. In a buttonhole making machine of the type having a needle and a co-operating work clamp reciprocable in a transverse direction, an attachment, in combination with said needle and work clamp, including means for supporting the work in operative position with a portion thereof under said work clamp, means for moving said work supporting means simultaneously with and in a path duplicating the transverse movement of said work clamp, means for feeding said work supporting means in a direction substantially normal to said transverse direction past said work clamp, and means for intermittently stopping said feeding means in timed relation with the operation of said needle and work clamp to successively present thereto spaced areas of the work for the automatic production of a plurality of buttonholes therein.

3. In combination with buttonhole making machines of the type having a needle, a clutch and stop motion mechanism for said needle, and a co-operating work clamp reciprocable in a transverse direction, an attachment comprising means for supporting the work in operative posi-

tion with a portion thereof under said work clamp, means for power control of said clutch and stop motion mechanism, means for power control of said work clamp in timed relation with said clutch and stop motion mechanism, means for moving said work supporting means simultaneously with and in a path duplicating the transverse movement of said work clamp, and means operable in timed relation with said needle and said work clamp for intermittently feeding said work supporting means longitudinally past said work clamp for the automatic production of a plurality of buttonholes in said work.

4. In combination with buttonhole making machines of the type having a needle, a clutch and stop motion mechanism for said needle, and a cooperating work clamp reciprocable in a transverse direction, an attachment comprising means for supporting the work in operative position with a portion thereof under said work clamp, means for power control of said work clamp in timed relation with said clutch and stop motion mechanism, means for moving said work supporting means simultaneously with and in a path duplicating the transverse movement of said work clamp, and means operable in timed relation with said needle and said work clamp for intermittently feeding said work supporting means longitudinally past said work clamp for the automatic production of a plurality of buttonholes in said work.

5. In combination with buttonhole making machines of the type having a needle, a clutch and stop motion mechanism for said needle, and a cooperating work clamp reciprocable in a transverse direction, an attachment comprising means for supporting the work in operative position with a portion thereof under said work clamp, means for power control of said clutch and stop motion mechanism, means for moving said work supporting means simultaneously with and in a path duplicating the transverse movement of said work clamp, and means operable in timed relation with said needle and said work clamp for intermittently feeding said work supporting means longitudinally past said work clamp for the automatic production of a plurality of buttonholes in said work.

6. The combination of claim 1, wherein the work clamp includes a base and wherein the means for moving said work supporting means includes an arm operably connected to the base at one end and to the work supporting means at the other end.

7. The combination of claim 1, wherein the feeding means includes a continuously turning lead screw.

8. The combination of claim 1, wherein the feeding means includes a continuously turning lead screw and a threaded shoe member releasably engageable with said lead screw.

9. The combination of claim 1, wherein the work supporting means includes a table and a clamp mechanism on said table.

10. The combination of claim 1, wherein the work supporting means includes a spring-loaded canted roller mounted on the machine and contacting the work to exert a component of force thereon in a direction toward said work clamp.

11. The combination of claim 1, including a framework, wherein the work supporting means includes a table, a pair of table supporting members, means adjustably connecting said table to said supporting members, and a pair of block members operably connected to said framework, said table supporting members being slidably mounted on said block members.

12. The combination of claim 11, wherein said framework is provided with a plurality of elongated support rods and said block members being provided with openings through which said rods pass for sliding movement of said block members with respect to said framework.

13. In a buttonhole making machine of the type having a needle and a co-operating work clamp reciprocable in a transverse direction, an attachment, in combination with

said needle and work clamp, including a framework; means for supporting the work in operative position with a portion thereof under said work clamp, said means including a table; a block member operably connected to said framework for movement in a direction substantially perpendicular to the transverse movement of said work clamp; means on said framework for intermittently moving said block member in said direction; a table supporting member operably connected to said block member for reciprocable movement in directions substantially parallel to the transverse movement of said work clamp, said table being rigidly connected to said table supporting member; and means for moving said table supporting member simultaneously with and in a path duplicating the transverse movement of said work clamp.

14. In a buttonhole making machine of the type having a needle and a cooperating work clamp reciprocable in a transverse direction, an attachment, in combination with said needle and work clamp, including a framework; means for supporting the work in operative position with a portion thereof under said work clamp, said means including a table; a pair of block members operably connected to said framework for movement in a direction substantially perpendicular to the transverse movement of said work clamp, one of said block members being positioned on either side of said work clamp; means on said framework for intermittently moving said block members in said direction; a pair of table supporting members, one operably connected to each of said block members for reciprocable movement in directions substantially parallel to the transverse movement of said work clamp, said table being rigidly connected to said table supporting members; and means for moving said table supporting members simultaneously with and in a path duplicating the transverse movement of said work clamp.

15. The combination of claim 14, wherein said framework is provided with a plurality of elongated support rods, said block members being provided with openings through which said rods pass for sliding movement of said block members with respect to said framework.

16. The combination of claim 14, wherein said framework is provided with a plurality of elongated support rods, said block members being provided with openings

through which said rods pass for sliding movement of said block members with respect to said framework, and wherein each block member carries a pair of rods extending substantially perpendicular to the openings in said block members, the table supporting members being provided with openings through which said last named rods pass for sliding movement of said table supporting members with respect to said block members.

17. In a buttonhole making machine of the type having a needle and a cooperating work clamp reciprocable in a transverse direction, an attachment, in combination with said needle and work clamp, including a framework; means for supporting the work in operative position with a portion thereof under said work clamp, said means including a table; a pair of block members operably connected to said framework for movement in a direction substantially perpendicular to the transverse movement of said work clamp, one of said block members being positioned on either side of said work clamp; means on said framework for intermittently moving said block members in said direction; a pair of table supporting members, one operably connected to each of said block members for reciprocable movement in directions substantially parallel to the transverse movement of said work clamp, said table being rigidly connected to said table supporting members; and means for moving said table supporting members simultaneously with and in a path duplicating the transverse movement of said work clamp, said last named means including an operative connection between said table supporting members and said work clamp.
